[57] CLAIM

The ornamental design for a key telephone set with
speakerphone and visual display panel, as shown and
described.

DESCRIPTION

FIG. 1 is a front elevational view of a key telephone set
with speakerphone and visual display panel showing
our new design in cradled relationship;

FIG. 2 is a top plan view thereof;

FIG. 3 is a rear elevational view thereof;
FIGS. 4 and 5 are respectively right and left side eleva-
tional views thereof;

FIG. 6 is a bottom plan view thereof; and

FIG. 7 is a front, top and right side perspective view
thereof.

FIG.1
